PERCUSSIVE TOOL

Filed March 22, 1927

UNITED STATES PATENT OFFICE

WILLIAM R. WILLIAMS, OF KENT, OHIO, ASSIGNOR TO THE DAVEY TREE EXPERT CO.,
OF KENT, OHIO, A CORPORATION OF OHIO

PERCUSSIVE TOOL

Application filed March 22, 1927. Serial No. 177,290.

My said invention relates to a percussive tool having a holder or chuck for a tool e. g. of the reciprocatory pneumatic type in which the tool is not operated until it has been placed against the work and forced back against a rapidly vibrating plunger. In tree surgery, to which my device is peculiarly adapted, it is often necessary to work with the tool pointing upward and in such cases the tool, here shown as a chisel, will fall back repeatedly on the vibrating plunger and be thrown up against the shoulder limiting its outward movement, with the result that the said shoulder and the coacting shoulder of the tool will be injured by the unnecessary hammering. It is an object of my invention to avoid this hammering action. Whether the tool points upward or horizontally it is frequently driven with great force out of the chuck if it happens to be turned into releasing position and so may do serious damage, which is avoided according to my invention by the use of an improved retainer.

Another object of my invention is to provide a quickly detachable connection for the tool.

Referring to the drawings, which are made a part of this application and in which similar reference characters denote similar parts:

Fig. 1 is an elevation of the forward end of a pneumatic hammer chuck and a tool operated thereby, with certain parts broken away,

Fig. 2, a fragmentary vertical section of the device in working position,

Fig. 3, an elevation of a chuck casing or sleeve,

Fig. 4, an end view of the same,

Fig. 5, an end view of the chuck housing and plunger with the tool and associated parts omitted,

Fig. 6, a detail of a key ring,

Fig. 7, a section on line 7—7 of Fig. 2,

Fig. 8, a detail of a locating ring,

Fig. 9, a side view of the same,

Fig. 10, a detail of a locking ring,

Fig. 11, a side view of the same,

Fig. 12, a section of the tool on line 12—12, and

Fig. 13, a section of the tool shank on line 13—13.

In the drawings, reference character 20 indicates the reduced end of the housing a suitable tool holder containing a vibratory 55 percussion member 19 for actuating the tool 21 by blows of the percussion member, which is mounted for longitudinal movement in the housing 22.

A knurled tool retainer 23 encloses the end 60 and serves as a guard to prevent injury to the operator's hands or clothing by the moving parts inside said retainer. At its forward end the retainer has an opening 24 corresponding in shape to a collar 25 on the 65 tool (Fig. 7), and at opposite sides of the opening there are two shoulders 26 (Fig. 4) on which the enlarged parts of the collar 25 may rest. The housing has a non-circular recess at 27 (Fig. 5) providing a seat for the 70 correspondingly-shaped shank 27' of the tool.

Near the opposite end of the retainer there is a shoulder on which rests a locating ring 28 provided with two pins 29, said ring bearing 75 at its rear side against a shoulder on the housing 22. The pins 29 extend into apertures 30 in a locking ring 31 (Fig. 10) and the retainer 23 has shallow recesses cooperating with apertures 30 to receive the pins and so 80 provide for relative positioning of the retainer and the ring 31. Screws 32 pass through holes 33 in the retainer and engage threaded apertures 34 in the locking ring to fix said parts together. 85

A spring 35 surrounds the housing 20, said spring bearing at one end against locking ring 31 and at the other against a key ring 36 (Fig. 6) having an elongated central opening at 37 and recesses at 38. The central opening corresponds to the approximately oblong shape of the lower end 39 of the housing (Fig. 5) and the recesses 38 correspond to the ears 40 whereby the ring may be slipped over the end of the housing, given a quarter 90 turn, and permitted to seat itself with the ears in recesses 38 whereby it is locked against rotation about the housing. 95

The device is assembled by positioning the locating ring 28 as in Fig. 2, then the lock- 100

ing ring 31 and the spring 35, then the key ring 36 is positioned in the manner above described, so that it holds the spring and the other rings in place. Then the retainer 23 may be slipped on, it being guided to place by pins 29 and secured by screws 32. The retainer is now given a quarter turn by hand to bring the opening 24 into position to allow the shank 27' to enter its seat, after which the 10 retainer is turned back a quarter turn to secure the tool in place.

It will be seen that the tool can be very quickly released and replaced by the means described and that the friction between the 15 housing and the locating ring due to the spring will prevent accidental rotation of the retainer. In addition to this the spring 35 serves to cushion the movement of the retainer under the impact of its impelling 20 means and so prevent injury to the collar 25 and the ears 26, while also holding the tool against rotation relatively to the housing.

It will be obvious to those skilled in the art 25 that my construction as disclosed may be varied in many ways without departing from the spirit of the invention and therefore I do not limit myself to the specific form of the invention shown in the drawings and described in the specification, but only as indicated in the appended claims.

Having thus fully described my said invention, what I claim as new and desire to secure by Letters Patent is:

1. The combination with a housing having 35 a bore, an impelling member in the bore, a tool having a non-circular shank fitting in a correspondingly shaped part of the bore, a tool retainer about the outer end of the housing, and a spring inside the retainer for forcing the retainer toward the inner end of the housing, of interengaging means on the 40 retainer and tool adapted to release the tool on rotation of the retainer about the housing, and means for frictionally resisting rotation of the housing comprising oppositely 45 facing shoulders on the housing and the retainer, a locating ring fitting between said shoulders, and means on the housing and the retainer for holding the spring under compression, substantially as set forth.

2. The combination with a housing having 55 a bore, an impelling member in the bore, a tool having a non-circular shank fitting in a correspondingly shaped part of the bore, a tool retainer about the outer end of the housing, and a spring inside the retainer for forcing the retainer toward the inner end of the housing, of interengaging means on the 60 retainer and tool adapted to release the tool on rotation of the retainer about the housing, and means for frictionally resisting rotation of the retainer comprising oppositely 65 facing shoulders on the housing and the retainer, a locating ring fitting between said shoulders, means on the housing for

supporting the outer end of the spring, and a locking ring fixed to the interior of the retainer in position to compress said spring said locking ring having its upper face on a level with the shoulder on the retainer, whereby said locating ring supports the locking ring against shocks tending to separate it from the retainer and said locating ring also acts as a brake against circumferential movement of the retainer.

3. The combination with a housing having a bore, an impelling member in the bore, a tool having a non-circular shank fitting in a correspondingly shaped part of the bore, a tool retainer about the outer end of the housing, and a spring inside the retainer for forcing the retainer toward the inner end of the housing, of interengaging means on the retainer and tool adapted to release the tool on rotation of the retainer about the housing, and means for frictionally resisting rotation of the retainer comprising oppositely facing shoulders on the housing and the retainer, a locating ring fitting in the retainer with its inner face in the same plane as that of the shoulder in the retainer, said locking ring holding the spring under compression, screws passing through the retainer into the locking ring, and pins on the locating ring entering mating recesses in the locking ring and the retainer to insure registration of the screw holes in said parts, substantially as set forth.

4. The combination with a housing having a bore, an impelling member in the bore, a tool having a non-circular shank fitting in a correspondingly shaped part of the bore, a tool retainer about the outer end of the housing, and a spring inside the retainer for forcing the retainer toward the inner end of the housing, of interengaging means on the retainer and tool adapted to release the tool on rotation of the retainer about the housing, means for frictionally resisting rotation of the retainer comprising a shoulder 100 on the housing, and means carried by the retainer including a face normally held in engagement with said shoulder by said spring, substantially as set forth.

In testimony whereof I affix my signature. 115
WILLIAM R. WILLIAMS.
